UNITED STATES PATENT OFFICE

SARAH W. HITCHCOCK, OF DIXON, ILLINOIS.

CHIPPED-ICE BOWL.

No. 885,475

Specification of Letters Patent. Patented April 21, 1908.

Application filed May 23, 1907. Serial No. 375,300.

To all whom it may concern:

Be it known that I, SARAH W. HITCHCOCK, a citizen of the United States, and a resident of the city of Dixon, in the county of Lee and State of Illinois, have invented certain new and useful Improvements in Chipped-Ice Bowls; and I do hereby declare that the following is a full, clear, and exact description of the same, reference being had to the drawings and to the letters of reference marked thereon, which form a part of this specification.

This invention relates to improvements in chipped ice bowls.

Devices of this class heretofore have usually been so constructed that the chipped ice and the water due to its melting are allowed to remain in the same receptacle, causing the remaining ice to melt more quickly and permitting considerable drip from the ice when removed from the bowl.

It is an object of this invention to provide a device of the class specified containing an independent compartment for the ice and a compartment, into which the water therefrom is collected thus at all times providing a comparatively dry ice chamber in which any article of food may be preserved from injury.

It is also an object of this invention to provide a very strong and durable device in which the ice receptacle is positively but removably supported on the water receptacle.

It is also an object of this invention to so construct the device that the strainer is secured to the ice receptacle and removable therewith thus obviating the necessity for first removing the ice into a separate bowl when emptying the water receptacle as heretofore.

The invention consists in the matters hereinafter described and more fully pointed out and defined in the appended claims.

In the drawings: Figure 1 is a vertical section of a device embodying my invention. Fig. 2 is a top plan view thereof with parts broken away. Fig. 3 is an enlarged fragmentary section taken transversely through the cover and ice receptacle rim. Fig. 4 is an enlarged fragmentary section taken through the rim of the water receptacle and wall of the ice receptacle.

As shown in said drawings:—A indicates the water receptacle which is constructed of metal or any suitable material and may be shaped by spinning, stamping or in any other preferred manner. Said receptacle as

shown is made of one piece of metal and the top thereof is turned to form an inwardly directed semi-circular bead *a* with the margin *a'* turned outwardly and parallel with the wall and inwardly closing on the inwardly turned bottom of the bead. The bead thus formed affords a broad bearing for the ice bowl or receptacle and also a neat finish.

The ice receptacle *B* as shown is also constructed of one piece of metal by pressing or spinning after which the rim *b* is rolled to form a smooth edge. From a point below the middle the wall of the receptacle inclines inwardly to afford downwardly facing peripheral shoulder *b'* to rest upon the bead *a*. The bottom of the ice bowl is perforated as shown in Figs. 1 and 2. A cover *C* also constructed in one piece is provided which is concave on its under side and provided with an inwardly curved flange *c* to rest on and fit to the rim of the receptacle *B* as shown in Fig. 1. A suitable handle *c'* is secured to the cover *C* at the apex thereof and a handle *D* is rigidly secured to the water receptacle *A* for carrying the bowl.

The operation is obvious and it is seen that the bearings formed are large, also owing to the telescoping connection between the receptacle that a very substantial structure is formed insuring a tight fit.

By having the bottom *b''* of the receptacle perforated a very effective strainer is produced which permits escape of the water from the ice receptacle into the water receptacle keeping the ice comparatively dry and retarding the melting thereof.

Material in the ice bowl can never be covered by water from the melting of the ice. To dump the water from the receptacle it is necessary only to remove the ice receptacle thus obviating the necessity of scooping the ice into a separate bowl as usually is the case with bowls constructed of a single receptacle with a strainer loosely seated therein. Any material may be used in the construction and many details may be varied without departing from the principles of this invention.

I claim as my invention:

1. In a device of the class described a water receptacle having its wall inwardly curved at the top and a vertical outer part equal in length to the diameter of the curved part and flush with the wall, a handle rigidly secured to the water receptacle, an ice receptacle formed with a circumferential shoulder near the bottom thereof adapted to rest

on and conform to the shape of the curved top wall, a bead formed at the top of the ice receptacle, said ice receptacle having its wall above the shoulder flush with the wall of the water receptacle, a cover for the ice receptacle and a triangular bead at the edge of the cover having one side concaved to fit the bead of the ice receptacle.

2. In a device of the class described the combination with a water receptacle having its wall curved inwardly at the top forming an inward bead and an outer shoulder and the upper extremity of the wall folded downwardly and resting on the shoulder, an ice receptacle reduced in diameter at its lower end resting on said bead, a perforated bot-

tom integral with the reduced part of the ice receptacle, said ice receptacle having a rounded top, a cover having a somewhat triangular bead with one side concaved to the top of the ice receptacle and having the lower edge of the bead locking within the top of the ice receptacle and handles, one for the cover and one for the water receptacle.

In testimony whereof I have hereunto 25 subscribed my name in the presence of two subscribing witnesses.

SARAH W. HITCHCOCK.

Correction in Letters Patent No. 885,475.

It is hereby certified that in Letters Patent No. 885,475, granted April 21, 1908, upon the application of Sarah W. Hitchcock, of Dixon, Illinois, for an improvement in "Chipped-Ice Bowls," an error appears in the printed specification requiring correction, as follows: On page 2, line 20, after the word "to" the word *fit* should be inserted; and that the said Letters Patent should be read with this correction therein that the same may conform to the record of the case in the Patent Office.

Signed and sealed this 12th day of May, A. D., 1908.

C. C. BILLINGS,
Acting Commissioner of Patents.

on and conform to the shape of the curved top wall, a bead formed at the top of the ice receptacle, said ice receptacle having its wall above the shoulder flush with the wall of the water receptacle, a cover for the ice receptacle and a triangular bead at the edge of the cover having one side concaved to fit the bead of the ice receptacle.

2. In a device of the class described the combination with a water receptacle having its wall curved inwardly at the top forming an inward bead and an outer shoulder and the upper extremity of the wall folded downwardly and resting on the shoulder, an ice receptacle reduced in diameter at its lower end resting on said bead, a perforated bot-

tom integral with the reduced part of the ice receptacle, said ice receptacle having a rounded top, a cover having a somewhat triangular bead with one side concaved to the top of the ice receptacle and having the lower edge of the bead locking within the top of the ice receptacle and handles, one for the cover and one for the water receptacle.

In testimony whereof I have hereunto 25 subscribed my name in the presence of two subscribing witnesses.
